C. E. PRICE,
MUFFLER FOR EXHAUST GASES,
APPLICATION FILED APR. 14, 1920.

Patented June 28, 1921.

CHARLES E. PRICE INVENTOR.

BY *A. B. Bourneau*
ATTORNEY

UNITED STATES PATENT OFFICE.

CHARLES E. PRICE, OF SAN DIEGO, CALIFORNIA, ASSIGNOR OF ONE-HALF TO G. M. ALEXANDER, OF SAN DIEGO, CALIFORNIA.

MUFFLER FOR EXHAUST-GASES.

1,383,150.

Specification of Letters Patent. Patented June 28, 1921.

Application filed April 14, 1920. Serial No. 373,793.

To all whom it may concern.:

Be it known that I, CHARLES E. PRICE, a citizen of the United States, residing at San Diego, in the county of San Diego and State of California, have invented certain new and useful Improvements in Mufflers for Exhaust-Gases, of which the following is a specification.

My invention relates to a muffler for deadening the sound of the exhaust from internal combustion engines and the objects of my invention are: first, to provide a muffler for deadening the sound of the exhaust vapors from internal combustion engines; second, to provide a device of this class which retards the flow of the exhaust vapors after leaving internal combustion engines; third, to provide a device of this class in which the exhaust vapor is caused to circulate in opposite directions in said muffler and is retarded in its flow by reason of its counteraction; fourth, to provide a device of this class which is easy to disassemble and repair and, fifth, to provide a device of this class which is very simple and economical of construction, durable, easy to install, applicable for use with the different makes of engines now in use, very efficient in its action and which will not readily deteriorate or get out of order.

With these and other objects in view as will appear hereinafter my invention consists of certain novel features of construction, combination and arrangement of parts and portions as will be hereinafter described in detail and particularly set forth in the appended claims reference being had to the accompanying drawings and to the characters of reference thereon which form a part of this application in which:

Figure 1 is a longitudinal sectional view of my muffler through 1-1 of Fig. 3; Fig. 2 is a sectional view through 2-2 of Fig. 1 and Fig. 3 is a sectional view through 3-3 of Fig. 1.

Similar characters of reference refer to similar parts and portions throughout the several views of the drawings.

The inlet member 1, outlet member 2 cylindrical casing 3, rods 4, frusto-conical partition members 5, 6, 7, 8, 9, 10, 11 and 12, vanes 13 and frusto-conical member 14 constitute the principal parts and portions of my muffler.

The inlet and outlet members 1 and 2 are

substantially duplicates in form. They are provided with flanges 1^a and 2^a, adapting them to be connected to exhaust conductors and are provided with frusto-conical shaped portions 1^b and 2^b and on the perimeter are provided with lugs 1^c and 2^c provided with holes adapted for the rods 4. In this case I have shown three, though it is obvious that there may be any number. Secured between the members 1^b and 2^b positioned in the notches 1^d and 2^d is the cylindrical casing 3. Mounted in this cylindrical casing 3 are the cone and frusto-conical shaped partitions 5 to 12 inclusive. It will be noted that the inlet openings in these frusto-conical members decrease in diameter toward the outlet end of the muffler and that the outer diameter of these frusto-conical members decrease in diameter, thus providing for a proportionate distribution of the exhaust vapors from the engine between the several frusto-conical members. These frusto-conical partition members are supported by means of lugs *a* extending from said partitions and provided with holes through which the rods 4 pass and mounted on said rods between the lugs *a* are separator sleeves 4^a for holding said partitions in certain spaced relation and said rods 4 are threaded some distance from their ends and nuts 4^b provided for supporting the several partitions so that they may be removed from the casing 3 in their united form. Mounted on the face of these frusto-conical members toward the inlet of the muffler are a plurality of curved vanes which tend to direct the course of the exhaust vapors in its course outwardly toward the casing and outlet. It will be noted that these vane members are positioned so that the curves are in opposite directions on the alternate frusto-conical members so that the exhaust is directed in opposite directions with each alternate frusto-conical member, thus causing it to unite while passing in opposite directions, after passing through between the frusto-conical members and causing retardation of its flow. It will be noted that the cone member 12 has no opening and the remaining exhaust must pass around the same. Mounted in the outlet end is a frusto-conical member 14 which is provided with perforations to permit the exhaust vapors to pass through as well as permit a certain portion to pass through the opening.

Though I have shown and described a

particular construction, combination and arrangement of parts and portions I do not wish to be limited to this particular construction, combination and arrangement but 5 desire to include in the purview of my invention the construction, combination and arrangement substantially as set forth in the appended claims.

It is obvious that with this construction 10 there is provided a muffler wherein the exhaust vapors from a gas engine is caused to circulate in opposite directions in alternate layers, causing it to unite in its passage from between the partitions, causing retardation of its flow; that the openings in the 15 several partitions are graduated, thus distributing the volume proportionately between the various partitions and providing additional retardation through perforations 20 near the outlet of the muffler thus providing for counteraction of the circulation of the exhaust vapors through the muffler.

Having thus described my invention what I claim as new and desire to secure by Letters Patent is:

1. A muffler for exhaust gases, including a casing, a plurality of partitions therein provided with gradually decreasing inlet openings centrally in said partitions and 30 with gradually increasing outlet openings at the outer edge of said partitions.

2. A muffler for exhaust gases, including a casing, a plurality of partitions therein provided with gradually decreasing inlet openings centrally in said partitions, with gradually increasing outlet openings at the outer edge of said partitions and curved vanes secured between said partitions positioned to direct the gases in opposite directions between the alternate partitions.

3. A muffler for exhaust gases, including a casing, a plurality of partitions therein provided with gradually decreasing inlet openings centrally in said partitions and 45 with gradually increasing outlet openings at the outer edge of said partitions and a perforate member in the outlet end of said casing.

4. A muffler for exhaust gases, including 50 a casing, a plurality of partitions therein provided with gradually decreasing inlet openings centrally in said partitions, with gradually increasing outlet openings at the outer edge of said partitions, curved vanes secured between said partitions positioned to direct the gases in opposite directions between the alternate partitions and a perforate frusto-conical member in the outlet end of said casing.

5. A muffler for exhaust gases, including 60 a cylindrical casing, inlet and outlet members for supporting said casing, a plurality of frusto-conical shaped partitions with gradually decreasing inlet openings toward the outlet end of said casing and gradually increasing outlet openings toward said outlet end.

6. A muffler for exhaust gases, including a cylindrical casing, inlet and outlet members for supporting said casing, a plurality of 70 frusto-conical shaped partitions with gradually decreasing inlet openings toward the outlet end of said casing and gradually increasing outlet openings toward said outlet end and curved vanes mounted on one side 75 of each of said partitions positioned with the curves in opposite directions on each alternate partition whereby exhaust gases are conducted in opposite direction between the alternate partitions.

7. A muffler for exhaust gases, including a cylindrical casing, inlet and outlet members for supporting said casing, a plurality of frusto-conical shaped partitions with gradually decreasing inlet openings toward the 80 outlet end of said casing and gradually increasing outlet openings toward said outlet end, curved vanes mounted on one side of each of said partitions positioned with the curves in opposite directions on each alternate partition whereby exhaust gases are conducted in opposite direction between the alternate partitions and a perforate frusto-conical shaped partition in the outlet end of 85 said casing.

8. A muffler for exhaust gases, including a cylindrical casing, inlet and outlet members for supporting said casing, a plurality of frusto-conical shaped partitions with gradually decreasing inlet openings toward the 95 outlet end of said casing and gradually increasing outlet openings toward said outlet end, curved vanes mounted on one side of each of said partitions positioned with the curves in opposite directions on each alternate partition whereby exhaust gases are conducted in opposite direction between the alternate partitions, a perforate frusto-conical shaped partition in the outlet end of said casing and rod means for connecting said 100 cylindrical casing with the inlet and outlet supporting members adapted to engage said partitions for supporting them in position.

In testimony whereof, I have hereunto set my hand at San Diego, California, this 8th day of April, 1920.

CHARLES E. PRICE.
